UNITED STATES PATENT OFFICE.

CHARLES D. SEEBERGER, OF NEW YORK, N. Y., ASSIGNOR TO OTIS ELEVATOR COMPANY, A CORPORATION OF NEW YORK.

CONVEYER.

1,023,443.

Specification of Letters Patent. Patented Apr. 16, 1912.

Application filed June 7, 1902. Serial No. 110,641.

To all whom it may concern:

Be it known that I, CHARLES D. SEEBERGER, a citizen of the United States, residing at New York, in the county of New 5 York and State of New York, have invented certain new and useful Improvements in Conveyers, of which the following is a specification.

My present invention is concerned with 10 certain improvements in that form of a conveying apparatus known as moving stairways or inclined footways, and is designed primarily to produce a device of the class described in which the horizontal portions 15 of the carrier constituting the landings shall run more slowly than the inclined portion constituting the inclined run, so that although the apparatus is run at a comparatively high rate of speed in order to convey 20 passengers rapidly from one floor to another, yet it will be easy to get on and off of the same at the landing.

My invention is further concerned with 25 an auxiliary landing which may be applied to any ordinary type of moving stairway, and which runs at a lower rate of speed than the footway so that by stepping from the rapidly moving footway to the more slowly moving auxiliary landing, and thence 30 to the stationary floor, or vice versa, it is possible to get off and on the footway safely although it is running at a high rate of speed.

Another feature of my invention is a novel 35 cable driving mechanism which I employ.

Still another feature of the invention is a novel linkage system connecting the steps and for determining the distance apart at 40 which they shall operate on the different portions of the track.

To illustrate my invention, I annex here- 45 to four sheets of drawings in which the same reference characters are used to designate identical parts in all the figures, of which—

Figure 1 is a side elevation, somewhat diagrammatic in its nature, showing the complete system, with some of the steps, and the tracks and supporting structure omitted; Fig. 2 is a plan view of the same; Fig. 3 is an elevation, partly in section and also somewhat diagrammatic in its nature, showing a portion of the upper end on an enlarged scale; Fig. 4 is a plan view of the driving mechanism shown in Fig. 3; Fig. 5 is a view similar to Fig. 3 but showing the

lower end of the apparatus; Fig. 6 is a plan view of the driving mechanism shown in Fig. 5; Fig. 7 is a sectional view of the driving mechanism at the upper end of the apparatus on the line 7—7 of Fig. 3; Fig. 8 is a front elevation on an enlarged scale of one of the grip mechanisms attached to each step for holding the driving cables, with the inclosing casing in section; Fig. 9 is a similar view in side elevation of the mechanism shown in Fig. 8; and Fig. 10 is a detached view in side elevation of the linkage spacing the steps and the mechanism employed for automatically shortening the same when the steps are telescoped on the landings.

Each step 20 is composed of a plurality of ribs or brackets 21, rigidly secured upon the axles 24, which have the yokes 22 rigidly secured near the ends thereof, which in turn 75 have the wheels journaled thereon, the front wheels 23 being in different vertical planes from the rear wheels 25, so that they can operate on the lower tracks 26 on the inclined portion while the rear wheels operate on 80 the upper tracks 27 so that the tread surfaces shall be held horizontal, the general arrangement of the trucks and tracks being the same as shown in my application No. 79,520, filed October 22, 1901, now Patent 85 No. 994,879 dated June 13, 1911. The tracks 26 and 27 are on substantially the same horizontal levels at the landings and on different levels on the inclined carrying portion, the arrangement of the tracks in this respect 90 corresponding to that of the aforesaid application.

The brackets or ribs 21 on the alternate steps are, as best seen in Fig. 2, staggered or differently spaced, so that they can intermesh on the lower landing where they are driven by the cable 28 and on the upper landing where they are driven by the cable 30, the steps being separated on the inclined portions where they are driven by the more rapidly moving cable 29, the spaces between the riser-portions of the ribs or brackets providing vertical grooves or slots in which the projecting forward ends of the off-set or staggered tread-portions of the ribs or brackets of an adjacent step intermesh or telescope. By this construction and arrangement of parts, it will be seen that the steps move slowly on the landings where the passengers get on and off, and move rapidly 100 105 110

on the inclined portions where the passengers are standing stationary, so that there is less danger of the passengers being overthrown by the momentum of the apparatus, 5 while permitting it to operate at a high rate of speed between the floors.

The cables 28 and 30 are in a different vertical plane from the cable 29, and are preferably in the same vertical plane, so 10 that only two cable grip mechanisms 31 and 32 need be applied to each step to coöperate with all the cables used for propelling them, the grips 31 coöperating with the cable 29 and the grips 32 coöperating with 15 the cables 28 and 30. The details of these grips (which are all alike except that the grips 31 are operated from one side and the grips 32 from the other) are shown in Figs. 8 and 9, where it will be seen that a vertical 20 housing 33 is employed projecting downward from the bottom of the step preferably directly beneath the axle. The grip bar 34 is slidingly mounted in this housing, and a strong helically coiled expanding 25 spring 35 is placed in the housing above the grip bar so that it tends to force the angular jaw 36 constituting the lower end of the grip bar down upon the cable. To force the cable into engagement with the jaw 30 firmly enough to compel the step to move with the cable, the dog 37 is pivoted to the side of the housing 33 as at 38 and has its lower end 37^a shaped so as to swing upward and force the cable into the jaw. A helically coiled expanding spring 39 is interposed 35 between the upper end of the dog 37 and the housing 33 in position so as to automatically hold the dog in engaging position. At suitable points where the cables 40 are to be picked up and dropped, I locate the grip operating cam strips 40, which are supported by brackets from the stationary shafts 42 and 66 upon which the cable sheaves to be described rotate, and are so 45 shaped as to coöperate with the upper end of the dog 37 to swing it into position at the time the cable is to be gripped or released, as will be readily apparent. There are eight of these cam strips 40, two being 50 located both above and below the stationary shafts 42 and 66 referred to where the inclined portion meets the two landings, it being understood that Fig. 8 represents the entry-end of one of the strips before its 55 cam surface comes into play.

To gradually reduce the rate of speed when the steps pass from the cable 29 to the cable 30, and to assist in properly spacing the steps for the upper landing, I preferably employ a pair of sprocket wheels 41 60 loosely mounted upon the horizontal shaft 42 supported in suitable bearings 43 secured to the supporting structure 44, as clearly shown in Fig. 7. These sprocket wheels 65 are driven by the means to be described,

and the spurs 45 on their peripheries engage with the axles 24 of the steps at the time the steps are released from the cable 29 and move them to the point where they grip the cable 30. The angular velocity of the 70 sprocket wheels 41 is such that they carry the steps at a speed intermediate of the speeds at which they are carried by the cables 29 and 30, so that the steps will be properly spaced and the jar which would result from suddenly transferring the steps from the rapidly moving cable 29 to the more slowly moving cable 30 will be divided. I may employ similar sprockets at the lower landing for like reasons. 80

To drive the cables 29 and 30 and the sprocket wheels 41, I employ a worm 46 which may be fastened to the armature shaft of a motor or any other rapidly rotating source of power. This worm 46 meshes 85 with a worm gear 47 secured upon the shaft 48 journaled in suitable bearings (not shown) on the supporting structure 44. Secured upon the shaft 48 are the gear wheels 49 which mesh with the gear wheels 50 rigidly secured to the sprocket wheels 41, which as before stated are loosely mounted on the shaft 42. Nearer the central portion of the shaft 48 and at one side thereof is secured the gear wheel 51 which is preferably larger than the gear wheels 49, and meshes with a gear wheel 52 loosely mounted on the shaft 42 and necessarily somewhat smaller than the gear wheel 50. Rigidly secured to and rotating with the gear wheel 52 is the cable sheave 53 around which the cable 29 passes. This sheave is grooved on its outer periphery to accommodate the cable, and is provided, as are the other cable sheaves to be described, with the 90 notches 54 which are spaced apart a peripheral distance equal to the distance between the axles of the steps when they are connected to the cable 29. These recesses are of course necessary to accommodate the 95 cable grips 31 and 32. The gear wheels 50 and 52 are preferably separated by a stationary collar 55 secured to the shaft 42 between them, and toward the other end of the shaft 42 is a similarly shaped and located collar 56 which separates the gear wheel 50 and the gear wheel 57 secured to the cable sheave 58 over which the cable 30 passes. A driving gear wheel 59 secured upon the shaft 48 meshes with the gear 100 wheel 57, and as will be seen from an examination of Fig. 4, the diameter of the gear wheels 59 and 57 are respectively smaller and larger than those of the gear wheels 49 and 50 and 51 and 52, so that it 105 will be seen that the cable sheave 58 rotates at a certain angular velocity, the sprocket wheels 41 at a still greater angular velocity, and finally the cable sheave 53 operates at the greatest angular velocity so that the 110 115 120 125 130

above described rates of movements of the steps on the landing, on the incline and between the landing and the incline will be secured. A stationary collar 60 is preferably 5 interposed between the sheaves 53 and 58.

An idle cable sheave 61 journaled upon a suitable shaft 62 preferably supported from one side to economize on space for a motor, carries the cable 30, but it will be noted that 10 the cable grip recesses 54^a thereof are closer together as is necessary to accommodate the steps which are intermeshed in passing around the sheave.

At the lower end of the incline is a shaft 15 63 which may be geared to the shaft 48, or driven in perfect synchronism therewith by the cable 29 operating between sheaves 53 and 67. This shaft 63 has secured thereon the gear wheel 64 which meshes with a 20 smaller gear wheel 65 loosely mounted upon the bearing shaft 66, which is supported in any suitable manner upon the supporting frame of the machine. This gear wheel 65 has rigidly secured thereto the cable sheave 25 67, which together with the sheave 53 carries the cable 29. The cable grip recesses 54^b of this sheave are spaced apart a distance equal to the distance between the steps on the cable 28. Rigidly secured upon the 30 shaft 63 is a gear wheel 68, smaller in diameter than the gear wheel 64 and which meshes with the gear wheel 69 loosely mounted upon the shaft 66 and larger in diameter than the gear wheel 65. The cable 35 sheave 70 is rigidly secured to the gear wheel 69, and it, together with the idle cable sheave 71 mounted upon the shaft 72 suitably journaled in the supporting frame, carries the cable 28. The cable grip recesses 54^c on the sheave 71 are suitably 40 spaced apart to accommodate the grips at the speed the steps are traveling on the lower landing, and the cable grip recesses 54^d on the sheave 70 are similarly spaced 45 apart, the spacing apart of the recesses 54^a and 54^b, and the relative rates of rotation of the sheaves 70 and 67 being such that the recesses are substantially in register to accommodate the cable grips during the time 50 that they are being transferred from the cable 28 to the cable 29 on the ascent, and from the cable 29 to the cable 28 on the descent.

To hold the steps together and to assist in 55 properly spacing them in passing from the landings to the incline and vice versa, I may pivot on the extended outer ends of the shafts 24 the links 73, each pair of which is pivotally connected between the 60 steps by the pins 74, upon each of which is mounted an anti-friction roller 75, which cooperates with guiding rails 76 located on the upper sides where the track passes from the incline to the horizontal and at the same 65 relative place on the return track. This

guide rail 76, of which only one on the upper side is shown, is suitably supported from the frame supports 44, and has the cam portion 77 projecting upward in the position to be struck by the anti-friction 70 rollers 75 as the steps in their extended position reach it. The rollers 75 contacting with the cam surface 77 are forced down so that the links are carried from the extended position shown at the left hand of 75 Fig. 10, which they occupy when the steps are on the incline, to the partially folded position shown at the right hand of said figure which they occupy when the steps are at the landing. This mechanism, as will 80 be seen, assists in forcing the steps to intermesh or telescope on the landings, and the cam surface 77 can be so shaped as to cooperate exactly with the spurs 45 on the sprocket wheels 41 in carrying the steps 85 from the extended to the intermeshed position.

The final feature of my invention is the auxiliary landing 78, which consists of a heavy belt mounted at the side of the landing and running around the driving pulley 79 at one end and the idle pulley or roller 80 at the other end. A plurality of supporting rollers 81 are mounted between the upper and lower portions of the belt, 90 and other supporting rollers 82 are preferably mounted beneath these rollers to carry the lower or return portions of the belt, the rollers being journaled in the brackets 83 supported from the frame work 100 44, as best seen in Fig. 7. One of the rollers 82 is so located as to hold the belt in engagement with the large driving roller 79 through substantially three quarters of its circumference in order that a strong driving power may be transmitted to the crossed belt. A belt or rope 84 running around a small belt wheel 85 secured on the shaft 48 and around the roller 79 serves to rotate the latter at the necessary rate of speed to 105 drive the belt in the same direction as but at a lineal velocity which is less than that of the steps passing beside it, so that the passenger stepping from the rapidly moving steps on the landing to the more slowly 110 moving auxiliary landing and thence to the stationary floor leaves the conveyer without any possibility of being jarred or upset by the movement thereof. A similar auxiliary landing may be mounted at the other 120 side of the upper landing, and may be mounted at either or both sides of the lower landing. I make no broad claim in this case to this feature as generically considered it forms part of the subject-matter of my 125 Patent No. 950,796, dated June 14, 1909, but confine my claims in the present case in this respect to the form of organization herein disclosed.

While I have shown my invention as 130

embodied in the form which I at present consider best adapted for illustrating its purposes, it will be understood that it is capable of wide modifications, and that I do not desire to be limited in the interpretation of the following claims except as may be necessitated by the state of the prior art.

What I claim as new, and desire to secure by Letters Patent of the United States is—

10 1. The combination with an endless movable carrier extending in an inclined run, of a side landing, said landing consisting of a fixed frame work and a traveling belt, and means for moving the upper surface of 15 the belt in the same direction as and at a less speed than the moving carrier.

2. The combination with an endless movable stairway, of a side landing, said landing consisting of a fixed frame work and a 20 traveling belt, and means for moving the upper surface of the belt in the same direction as and at a speed different from the speed of the moving stairway.

3. In a device of the class described, the 25 combination with ways, providing carrying runs, of a series of steps or supports mounted to travel on said ways, and means for driving said steps at different rates of speed on different portions of said carrying runs.

30 4. In a device of the class described, the combination with the ways consisting of the horizontal portions at different levels and the inclined portion connecting the same, of a series of steps or supports mounted to 35 travel on said ways, and means for driving said steps at a certain speed on the horizontal portions constituting the landings and at a greater speed on the inclined portion connecting the same.

40 5. In a device of the class described, the combination with ways, of a series of steps or supports mounted to travel on said ways, a plurality of cables driving said steps on different portions of the ways, and driving 45 mechanism for operating said cables at different rates of speed.

6. In a device of the class described, the combination with ways having the horizontal portions on different levels and the inclined portion connecting the same, of a 50 series of steps or supports mounted to travel on said ways, separate cables for driving said steps on the landings and on the inclined portions, and driving mechanism for 55 operating the cable on the inclined portion at a greater rate of speed than the cables on the horizontal portions.

7. In a device of the class described, the combination with ways, of a series of recessed steps adapted to intermesh and mounted to travel on said ways, and means for driving said steps at different rates of speed on different portions of said ways.

8. In a device of the class described, the 65 combination with the ways consisting of

the horizontal portions at different levels and the inclined portion connecting the same, of a series of recessed steps adapted to telescope and mounted to travel on said ways and forming landings on the horizontal portions and stairs on the inclined portions of said ways, and means for driving said steps slowly on the landings and telescoping them, and for driving them more rapidly on the incline and extending them.

70 9. In a device of the class described, the combination with the ways, of a series of telescoping steps or supports adapted to telescope and mounted to travel on said ways, a plurality of cables for driving said steps on different portions of the ways, and driving mechanism for operating said cables at different rates of speed.

75 10. In a device of the class described, the combination with the ways consisting of the horizontal portions on different levels and the inclined portions connecting the same, of a series of telescoping steps adapted to telescope and mounted to travel on said ways, separate cables for driving said steps on the horizontal and on the inclined portions, and driving mechanism for operating the cables on the horizontal portions or a slower rate of speed than the cable on the inclined portion.

80 11. In a device of the class described, the combination with the ways, of a series of steps or supports mounted to travel on said ways, means for driving said steps at different rates of speed on different portions of said ways, and link connections for spacing said steps apart the proper distance when they are traveling at different rates of speed.

85 12. In a device of the class described, the combination with ways, of a series of steps or supports mounted to travel on said ways, means for driving said steps at different rates of speed on different portions of said ways, links connecting said steps for spacing them apart the proper distance when they are traveling at different rates of speed, and mechanism coöperating with said links to force the steps together as they pass from a faster to a slower rate of movement.

90 13. In a device of the class described, the combination with the ways, of a series of steps or supports mounted to travel on said ways, means for driving said steps at different rates of speed on different portions of said ways, links connecting said steps for spacing them apart the proper distance when they are traveling at different rates of speed, and mechanism coöperating with said links to force the steps together as they pass from a faster to a slower rate of movement consisting of joints in said links between the steps, projections on said links, and a cam track coöperating with the projections to kink the chain formed by the links.

14. In a device of the class described, the combination with ways, of a series of steps or supports mounted to travel on said ways, a plurality of cables for driving said steps on different portions of the ways, and driving mechanism for operating said cables at different rates of speed consisting of driving sheaves concentrically mounted and driven at different rates of speed. 5 70
- 10 15. In a device of the class described, the combination with ways, of a series of steps or supports mounted to travel on said ways, a plurality of cables for driving said steps on different portions of the ways, driving 75
- 15 cable sheaves for two adjacent cables concentrically mounted, different sized gear wheels secured to said sheaves, and a driving shaft having gear wheels of different diameters secured thereon and meshing with 80
- 20 the gear wheels on the cable sheaves. 85
16. In a device of the class described, the combination with ways, of a series of steps or supports mounted to travel on said ways, a plurality of cables for driving said steps 90
- 25 on different portions of the ways at different rates of speed, cable grips on said steps, the driving cable sheaves concentrically mounted and having the cable grip recesses in their peripheries, and means for rotating 95
- 30 said sheaves at different rates of speed. 100
17. In a device of the class described, the combination with the ways having the horizontal portions on different levels and the inclined portions connecting the same, of a 105
- 35 series of steps or supports mounted to travel on said ways, a plurality of cables for driving said steps faster on the inclined portion than on the horizontal portions, and intermediate mechanism for carrying the steps 110
- 40 from the inclined cable to the horizontal cable. 115
18. In a device of the class described, the combination with the ways having the horizontal portions on different levels and the inclined portions connecting the same, of a 120
- 45 series of steps or supports mounted to travel on said ways, a plurality of cables for driving said steps faster on the inclined portion than on the horizontal portions, intermediate 125
- 50 mechanism for carrying the steps from the inclined cable to the horizontal cable, and means for driving said cables at different rates of speed and the intermediate mechanism at a rate of speed between that 130
- 55 of the two cables. 135
19. In a device of the class described, the combination with the ways consisting of the horizontal portions on different levels and the inclined portions connecting the same, 140
- 60 of a series of steps or supports mounted to travel on said ways, a plurality of cables for driving said steps on different portions of the ways, intermediate driving mechanism for carrying the steps from the inclined cable to the horizontal cable consisting of a 145
- 65 sprocket wheel coöperating with the steps, and means for driving said cables consisting of the cable sheaves concentrically mounted with each other and with the sprocket wheels. 150
20. In a device of the class described, the combination with the ways consisting of the inclined portion and the horizontal portion, of a series of steps or supports mounted to travel on said ways, two cables for driving 155
- 70 said steps at different speeds on the horizontal portion and the inclined portion, a shaft mounted adjacent the angle between the inclined and horizontal portions, a sprocket wheel having a gear wheel secured thereto 160
- 75 mounted to rotate on said shaft, two driving cable sheaves each having a gear wheel secured thereto and mounted to rotate on said shaft, and a parallel driving shaft having the three gear wheels secured thereon of different 165
- 80 diameters and meshing with the three gear wheels secured to the two driving cable sheaves and the sprocket wheel; all combined and coöperating substantially as and for the purpose described. 170
21. In a device of the class described, the combination with the ways, of the steps mounted to travel thereon, a cable traveling adjacent said ways, and grips on said steps adapted to coöperate with said cable. 175
22. In a device of the class described, the combination with the ways, of the steps mounted to travel thereon, links connecting said steps, a cable traveling adjacent said ways, and grips on said steps adapted to co- 180
- 90 operate with said cable. 185
23. In a device of the class described, the combination with the ways, of the steps mounted to travel thereon, links connecting said steps for spacing them apart and adapted to be moved to kink the chain on the end portion of the ways, and means to drive the steps. 190
24. In a device of the class described, the combination with the ways, of the steps mounted to travel thereon, links connecting said steps for spacing them apart, means for driving said steps, and means for moving said links at the end portions of the ways to kink the chain formed thereby and bring 195
- 100 the steps together. 200
25. In a device of the class described, the combination with the ways, of the steps mounted to travel thereon, a plurality of links connecting each adjacent pair of said steps and forming a chain for spacing them apart, a projection on one of the links between each pair of steps, and a cam track adapted to coöperate with said projection to kink the chain formed by the links and bring the steps together. 205
26. In a device of the class described, the combination with the ways having the inclined and horizontal portions, of the steps mounted to travel thereon at different 210

speeds and forming a landing on the horizontal portion, means for driving said steps, an auxiliary landing at the side of the landing formed by the steps, and means for driving said auxiliary landing at different speed from that of the steps.

27. In a device of the class described, the combination with the ways having the inclined and horizontal portions, of the steps 10 mounted to travel thereon at different speeds and forming a landing on the horizontal portion, means for driving said steps, an auxiliary landing at the side of the landing formed by the steps and consisting of an 15 endless belt, and means for driving the belt at a rate of speed slower than that of the steps.

28. In a device of the class described, the combination with ways having inclined 20 and horizontal portions, of steps mounted to travel thereon and forming a landing on the horizontal portion, means for driving said steps, an auxiliary landing adjacent the landing formed by the steps and consisting 25 of the belt wheels, supporting wheels between said belt wheels, a belt traveling over said wheels and supported thereby, and means for rotating one of the belt wheels to drive the belt at different speed from the 30 movement of the steps.

29. In a conveyer, the combination with ways providing carrying runs, of a series of steps or supports mounted to travel on said ways, means for driving said steps at different rates of speed on different portions of the carrying runs, an auxiliary landing, and means for moving the landing in the same direction as and at a less speed than the 35 steps.

30. In a conveyer, the combination of a framework, tracks thereon, having inclined and horizontal sections, a continuous footway traveling on said tracks, means whereby the speed of the footway is reduced at the 45 horizontal portions, an auxiliary landing, and means for moving the landing in the same direction as the footway.

31. In a device of the class described, the combination with the ways, of a series of 50 steps or supports mounted to travel on said ways, a plurality of cables driving said steps on different portions of the ways, means for automatically transferring the step from one cable to the other, and means 55 for driving said cables.

32. In a device of the class described, the combination with ways, of a series of steps or supports mounted to travel in said ways, a plurality of cables driving said steps on 60 different portions of the ways, driving mechanism for operating said cables at different rates of speed, and means for automatically transferring a step from one cable to another.

33. In a device of the class described, the

combination with ways, of a series of steps or supports mounted to travel on said ways, a plurality of cables driving said steps on different portions of the ways, driving means to operate the cables at different speeds, a grip for each cable on each step, and means for automatically releasing the grip from one cable and simultaneously clutching another cable with another grip. 70

34. In a device of the class described, the 75 combination with ways, of a series of steps or supports mounted to travel on said ways, a plurality of cables driving said steps on different portions of the ways, said cables having concentric sheaves at their overlapping ends, a grip for each cable on each step, and means for automatically releasing the grip from one cable and simultaneously clutching another cable with another grip. 80

35. In a device of the class described, the 85 combination with ways, of a series of steps or supports mounted to travel on said ways, a plurality of cables driving said steps on different portions of the ways, said cables having concentric sheaves at their overlapping 90 ends, a grip for each cable on each step having a movable dog, and means for automatically releasing the grip from one cable and simultaneously clutching another cable with another grip consisting of cam tracks adapted to cooperate with the movable dogs of the grips to release them or permit them to act, as the case may be. 95

36. In a device of the class described, the combination with ways, of a series of steps 100 or supports mounted to travel on said ways, a plurality of cables driving said steps on different portions of the ways, and having concentric sheaves at their overlapping ends with cable grip recesses in the peripheries 105 thereof, a grip for each cable on each step, and means for automatically releasing the grip from one cable and simultaneously attaching another grip to the other cable, said cable grip recesses being so spaced apart as 110 to register at the point of transfer as the sheaves are driven at their relative rates of speed.

37. In a device of the class described, the combination with the ways, of the steps supported on said ways forming carrying runs, and adapted to travel thereon at different predetermined speeds on the various portions of the carrying runs, and means for driving said steps. 115

38. In a device of the class described, the combination with the ways, of the steps mounted to travel thereon, and a cable drive for operating said steps on said ways. 120

39. In a device of the class described, the combination with the ways, of the telescoping steps mounted to travel thereon, and means for driving said steps. 125

40. In a device of the class described, a way providing an inclined run between dif- 130

ferent levels, a series of movable steps forming an inclined footway, means to move the steps on the run, the riser of each step provided with slots adapted to receive projections formed on the tread of an adjacent step at the levels.

41. In a device of the class described, a way providing an inclined run between different levels, a series of connected steps forming an inclined footway, means to move the steps on the run, each step having its tread portion composed of ribs and having vertical grooves in its riser adapted to receive the ends of the ribs of an adjacent step at the levels.

42. In a device of the class described, the combination with the ways, of the separate steps, a cable moving along the line of said ways, and a cable grip on each step.

43. In a device of the class described, the combination with the ways, including the horizontal and inclined portions, of the steps mounted to travel thereon, a pair of chains composed of links connecting said steps at each end, and means for automatically shortening both of said chains on part of the ways to bring the steps closer together while maintaining the same angle to each other.

44. In a device of the class described, the combination with the ways, including the horizontal and inclined portions, of the

steps mounted to travel thereon, a plurality of cables to which said steps are individually adapted to be attached, means for driving said cables at different rates of speed, a chain connecting said steps, and means for automatically shortening said chain as the steps pass from a faster to a slower cable, and vice versa.

45. In a device of the class described, the combination with the ways, including the horizontal and inclined portions, of the steps mounted to travel thereon, a chain composed of links connecting said steps, contacting members such as antifriction rollers upon alternate links of said chain, and a cam for engaging said contacting members for automatically shortening said chain on part of the ways to bring the steps closer together.

46. In a conveyer, the combination of a framework, tracks thereon, having inclined and horizontal sections, a continuous footway traveling on said tracks, and means whereby the speed of the footway is reduced at the horizontal portions, substantially as described.

In testimony whereof I affix my signature in presence of two witnesses.

CHARLES D. SEEBERGER.
